UNITED STATES PATENT OFFICE.

GEORGE L. SMITH, OF BROOKLYN, NEW YORK.

IMPROVEMENT IN FURNACE-GRATES.

Specification forming part of Letters Patent No. 40,712, dated November 24, 1863.

To all whom it may concern:

Be it known that I, GEORGE L. SMITH, of Brooklyn, in the county of Kings, in the State of New York, have invented a new and Improved Grate-Bearer for Steam Boiler and other Furnaces; and I do hereby declare that the following is a full and exact description thereof, reference being had to the accompanying drawings, and to the letters of reference once marked thereon.

The nature of my invention consists in constructing the upper edge or top of grate-bearers in such manner that the ashes, cinders, and clinkers which pass or drop through the openings or air-spaces in the grate will not lodge thereon and obstruct the free passage of air necessary for combustion and for keeping the grates cool.

I construct my grate-bearer in any of the known forms and apply thereto a sharp, contracted upper top surface, substantially as shown in the drawings, A A, Figures 1, 2, and 3.

The object of my invention is to lessen the wear and save in a measure the great expense of grates occasioned by fracture and burning out.

With the ordinary flat-top grate-bearer in use great loss to the grates is occasioned by the ashes, cinders, and clinkers, which bank up on the bearers and fill up the air-spaces in the grates, thus preventing the air from passing through that part of the grate which is over the bearers, which not only occasions the burning and melting of the grates, but obstructs the draft and renders that part of the furnace less effective as grate-surface. To obviate the difficulties arising from this cause I construct my bearer with its top or upper surface contracted or beveled, thus: A, as A A, Figs. 1, 2, and 3 in the drawings, so that the

bearer may not obstruct the openings for air in the grate, and likewise to allow the ashes and cinders to pass unobstructed to the ash-pit below.

Fig. 1 is a perspective view of bearers so constructed, with a section of grates lying thereon. Fig. 2 is a vertical transverse section of Fig. 1. Fig. 3 is another form of grate-bearer with my improvement.

A A marked on drawings is the beveled or contracted upper edge or top of the bearers.

The advantages of my invention are, first, an economy by lessening the liability of grates to burn or break; second, a free passage of air to support combustion through every and all parts of the grate lying thereon, thus making the whole area of the furnace an effective grate-surface; third, lessening the liability of the grates lying thereon to warp and spring.

Having thus fully described my invention and the mode of applying it, I remark that I do not claim to have invented a grate-bearer, except the beveled contracted upper edge or top; nor do I confine my invention to any particular form of bearer otherwise than the beveled top; neither do I confine my invention itself to any particular form or shape, except the beveled or contracted upper edge or top of grate bearers or supports; but

What I do claim as new, and desire to secure by Letters Patent of the United States, is—

The forming of grate-bearers for steam-boilers and other furnaces with the beveled or contracted top or upper surface, A, on which the grate-bars rest, substantially as and for the purpose set forth in the specification.

GEO. L. SMITH.
